UNITED STATES PATENT OFFICE.

HAROLD H. FEBREY, OF NEWARK, NEW JERSEY.

DESIGN FOR A BOOKRACK.

60,017.

Specification for Design.

Patented Dec. 20, 1921.

Application filed September 14, 1920. Serial No. 410,349. Term of patent 3½ years.

To all whom it may concern:

Be it known that I, HAROLD H. FEBREY, a citizen of the United States, residing at 347 Fourth avenue, Newark, New Jersey, have invented a new, original, and ornamental Design for Bookracks, of which the following is a specification, reference being had to the accompanying drawing, forming part thereof.

Figure 1 is an end elevation of the book rack;

Fig. 2 is a perspective view thereof.

The book rack B is formed of wire in the shape shown in the drawings and is carried by uprights A when the rack is to be mounted below a support.

I claim:

The ornamental design for a bookrack, as shown.

In witness whereof, I have hereunto signed my name.

HAROLD H. FEBREY.
